EDWARD S. MARKS, OF SYRACUSE, NEW YORK, ASSIGNOR TO H. H. FRANKLIN MANUFACTURING COMPANY, OF SYRACUSE, NEW YORK, A CORPORATION OF NEW YORK

AIR COOLING SYSTEM FOR AEROPLANE ENGINES

Application filed September 30, 1929. Serial No. 396,092.

This invention relates to air cooling means for line engines mounted in aeroplanes to actuate the propeller, particularly aeroplanes of the tractor type, and it has for its object, 5 a particularly simple and efficient means for supplying a cooling air current to the cylinders.

The invention consists in the novel features and in the combinations and constructions hereinafter set forth and claimed.

In describing this invention, reference is had to the accompanying drawing, in which like characters designate corresponding parts in all the views.

15 Figure 1 is a diagrammatic side elevation of an aeroplane embodying this invention.

Figure 2 is a front elevation of the front end of the casing of the engine.

Figure 3 is a fragmentary, sectional view 20 on line 3—3, Figure 2.

1 designates the aeroplane generally.

2 designates the engine mounted on the aeroplane, it being here shown as mounted at the front end of the frame or fuselage 3.

25 The engine is of the multi-cylinder, in line type and 4 designates the cylinders located one behind the other. The engine has the usual pistons, crank shaft etc.

The aeroplane here shown is of the tractor 30 type and 5 designates the propeller mounted on the front end of the crank shaft.

6 is the hood or casing around the engine, this being provided with louvers 7 in the side walls thereof. Also, the front of the

35 hood is provided with slots or louvers 8 which may be opened and closed by shutters as in automobile engines.

9 is the air conduit extending lengthwise of the engine cylinders and arranged to discharge air onto the cylinders and on the heads thereof, this conduit having a downwardly extending casing 10 at its front end which is provided with an air intake opening,

40 11 concentric with the crank shaft, as in the Franklin automobile air cooled engine. This opening 11 is arranged to receive some of the current of air from the propeller 5.

Means is also provided for creating an air current independently of the propeller, or for 45 boosting the air pressure delivered to the

opening by the propeller, and the means here shown is a centrifugal fan or blower 12 of any well known construction, this being mounted directly upon the crank shaft.

In operation, the propeller feeds air to the 55 intake opening of the air conduit and the fan feeds it with increased velocity through the air conduit to the engine cylinders and efficiently cools the engine, particularly when the plane is on the ground and the engine idling. When the plane is flying at such high 60 altitudes that the engine cools too much, the shutters at the front end of the engine casing may be closed more or less, thus cutting off the air intake from the air current created by 65 the propeller and also restricting the flow of air to the fan.

This air cooling system is particularly advantageous in that it provides a simple and economical way of adequately cooling line 70 engines in aeroplanes.

What I claim is:

1. In an aeroplane, a frame, a multi-cylinder, air cooled, in line internal combustion engine mounted on the frame with the cylinders one behind the other, a propeller connected to the crank shaft of the engine to be actuated thereby and located in front of the engine, an air conduit arranged to discharge air onto the cylinders to cool the same, the inlet end of said air conduit being arranged 75 in position behind the propeller to receive air therefrom, and means independent of the propeller, for supplying air to the conduit.

2. In an aeroplane, a frame, a multi-cylinder, air cooled, in line internal combustion engine mounted on the frame with the cylinders one behind the other, a propeller connected to the crank shaft of the engine to be actuated thereby and located in front of the engine, an air conduit arranged to discharge air onto the cylinders to cool the same, and a fan located in the conduit in juxtaposition to the inlet opening to supply air to the conduit independently of the propeller. 80

3. In an aeroplane, a frame, a multi-cylinder, air cooled, internal combustion engine mounted on the frame with the cylinders one behind the other, a propeller mounted on the front end of the crank shaft of the engine, an 85 90 95 100

air conduit arranged to discharge air onto the cylinders to cool the same, the air conduit having an intake opening at its front end in the rear of the propeller in position to receive 5 the current of air created by the propeller, and fan means within the conduit for increasing the air flow through the conduit.

4. In an aeroplane, a frame, a multi-cylinder, air cooled, in line internal combustion engine 10 mounted on the frame with the cylinders one behind the other, a propeller connected to the crank shaft of the engine to be actuated thereby and located in front of the engine, an air conduit arranged to discharge air onto 15 the cylinders to cool the same, the air conduit having an intake opening at the front end of the engine and in the rear of the propeller, a fan actuated by the engine located in said intake opening, a casing surrounding the engine 20 and open at its front end for receiving a portion of the air current from the propeller.

5. In an aeroplane, a frame, a multi-cylinder, air cooled, internal combustion engine mounted on the frame with the cylinders one 25 behind the other, a propeller mounted on the front end of the crank shaft of the engine, an air conduit arranged to discharge air onto the cylinders to cool the same, the air conduit having an intake opening located at its front 30 end in the rear of the propeller and concentric with the propeller, and in position to receive the current of air created by the propeller, and a fan mounted on the crank shaft in juxtaposition to said opening to create a 35 current of air through the opening and the conduit.

In testimony whereof, I have hereunto signed my name, at Syracuse, in the county of Onondaga, and State of New York, this 40 10th day of August, 1929.

EDWARD S. MARKS.
